PLASTIC SHEET MATERIAL

John R. Ellefson, Newburgh, N. Y.

Application June 5, 1958, Serial No. 51,214

Term of patent 14 years

(Cl. D87—3)

FIG. 1

FIG. 2

Figure 1 of the drawing is a plan view showing the continuous nature of my new design for plastic sheet material. Figure 2 is a cross sectional view taken on line 2—2 of Figure 1.

I claim:

The ornamental design for plastic sheet material, substantially as shown.
